CYLINDRICAL GRINDING MACHINE

Carl G. Flygare and Stewart S. Mader, Worcester, Mass., assignors to Norton Company, Worcester, Mass., a corporation of Massachusetts

Application March 4, 1941, Serial No. 381,710

10 Claims. (Cl. 51—95)

The invention relates to grinding machines, and more particularly to an improved cylindrical grinding machine.

One object of the invention is to provide a simple and thoroughly practical cylindrical grinding machine. Another object of the invention is to provide an improved table traversing and reciprocating mechanism. A further object of the invention is to provide a power operated grinding wheel feeding mechanism which is arranged for a continuous operation during a plunge-cut grinding operation or for an intermittent operation at the ends of the table stroke during a traverse grinding operation.

A further object of the invention is to provide an improved table dwell control mechanism whereby the table may be caused to dwell for a definite and predetermined time interval at the ends of its reciprocatory stroke. A further object of the invention is to provide a table reciprocating and reversing mechanism, in which a fluid shock absorbing device is provided between the reversing clutch and the table to eliminate shocks and vibrations incident to reversal which might be transmitted to the table. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved grinding machine;

Fig. 2 is a fragmentary vertical cross-sectional view, on an enlarged scale, taken approximately on the line 2—2 of Fig. 1;

Fig. 3 is a fragmentary vertical cross-sectional view, on an enlarged scale, taken approximately on the line 3—3 of Fig. 1;

Fig. 4 is a fragmentary vertical longitudinal sectional view, on an enlarged scale, of the table driving and reversing mechanism;

Fig. 5 is a fragmentary cross-sectional view, on an enlarged scale, taken approximately on the line 5—5 of Fig. 4, showing the shock absorbing device;

Fig. 6 is a fragmentary front elevation, on an enlarged scale, with the table reversing and stop-start levers shown in full lines and some of the interior mechanism shown in dotted lines;

Fig. 7 is a fragmentary horizontal sectional view, showing the reversing and stop-start clutches together with part of the actuating mechanism for the stop-start clutch; and

Fig. 8 is an electrical wiring diagram of the clutch shifting-time delay control mechanism.

A grinding machine has been illustrated in the drawings, comprising a base 10 which supports a longitudinally reciprocable work table 11 on the usual flat way 12 and V-way 13 (Fig. 2) for a longitudinal movement relative to the base 10. A rotatable work support is provided on the table 11, comprising a headstock 14 and a footstock 15 which are in turn provided with work supporting centers 16 and 17, respectively. The headstock 14 is preferably a motor driven headstock, in which an electric motor 18 is mounted on the upper portion of the headstock. The motor 18 is operatively connected by a belt drive (not shown) to rotate a face plate 19 which carries an adjustably positioned work driving pin or stud 20. It will be readily apparent from the foregoing disclosure that a work piece to be ground is mounted in supporting engagement on the headstock center 16 and footstock center 17 and is rotated by means of the driving pin 20 which preferably engages a driving dog adjustably attached to the left-hand end of a work piece.

The base 10 also serves as a support for a transversely movable grinding wheel slide 25. The wheel slide 25 supports a rotatable wheel spindle 26 in suitable bearings (not shown). The wheel spindle 26 serves as a support for a grinding wheel 27. An electric motor 28 is mounted on the upper surface of the wheel slide 25 and is connected by a belt drive contained within the guard 29 to rotate the spindle 26 and thereby to transmit a rotary motion to the grinding wheel 27.

The table 11 may be reciprocated longitudinally by means of a rack and gear mechanism, comprising a rack bar 35 depending from the under side of the table 20. A gear 36 which is supported on a rotatable shaft 37 meshes with the rack bar 35. The shaft 37 is journaled in suitable bearings (not shown) in the base 10. The shaft 37 also supports a worm gear 38 which meshes with a worm 39 which is either formed integral with or fixedly mounted on a shaft 40. The shaft 40 is journaled in anti-friction bearings 41 and 42 which are in turn supported in an apron 43. The apron 43 is fixedly mounted on the base 10.

A reversing mechanism is provided, comprising a pivotally mounted reversing lever 45 which is fixedly mounted on the outer end of a shaft

46 (Figs. 1 and 6). The reversing lever 45 is arranged to be shifted in either a clockwise or counterclockwise direction by means of a pair of adjustably mounted dogs 47 and 48 which are arranged in the path of a stud 49 carried by the reversing lever 45. The rock shaft 46 supports a downwardly extending arm 50 (Fig. 2) which is arranged to shift a yoke-shaped member 51 longitudinally when the reversing lever 45 is actuated by the table dogs 47 or 48. The yoke-shaped member 51 is arranged to straddle and engage a groove 52 formed in the periphery of a slidably mounted clutch member 53. The clutch member 53 is slidably keyed on a rotatable drive shaft 54 which is journalled in bearings 55 and 56.

When the clutch member 53 is shifted toward the right (Fig. 4), it engages or mates with clutch teeth 57 formed integral with a gear 58. The gear 58 is rotatably supported relative to the shaft 54 and meshes with a gear 59 which is keyed to a sleeve 60. The sleeve 60 is rotatably supported on a reduced portion 61 of the shaft 40. The outer end of the reduced portion 61 is rotatably supported by an anti-friction bearing 62. The sleeve 60 is operatively connected with the portion 61 of the shaft 40 in a manner to be hereinafter described.

When the clutch member 53 is shifted toward the left (Fig. 4), the clutch teeth on the right-hand end of the clutch member 53 will be shifted into engagement with a set of clutch teeth 63 formed integral with or fixedly mounted on a gear 64. The gear 64 is rotatably supported on the shaft 54 and meshes with an idler gear 65 which in turn meshes with a gear 66 formed integral with the sleeve 60. It will be readily apparent from the foregoing disclosure that when the clutch member 53 shifts toward the left (Fig. 4), a rotary motion will be transmitted by the shaft 54, through the clutch member 53, through the clutch teeth 63, the gear 64, the gear 65, and the gear 66, to rotate the sleeve 60 in the reverse direction.

A power operated driving mechanism is provided for rotating the shaft 54. This mechanism may comprise a change speed gear unit 70 which is fixedly mounted within the base 10 of the machine. Power is supplied to the gear unit 70 by means of a driving belt 71 from any suitable source of power such as, for example, an electric motor mounted on the rear of the base 10. The driving belt 71 drivingly engages a pulley 72 mounted on the right-hand end of a rotatable shaft 73. The shaft 73 is journalled at one end in an anti-friction bearing 74 which is supported in the casing 70. The other end of the shaft 73 is journalled in a bearing 75 formed in the hollow end of a rotatable shaft 76 to be hereinafter described. A clutch member 77 is slidably keyed on the shaft 73. A gear 78 is formed integral with the clutch member 77 and is arranged to be thrown into and out of mesh with a gear 79 which is keyed to the right-hand end of a rotatable shaft 80. The shaft 80 is journalled in suitable anti-friction bearings 81 and 82, respectively, which are supported in the housing 70. A gear 83 is formed integral with the shaft 80 and meshes with a gear 84 which is keyed to the right-hand end of the shaft 76. The clutch member 77 is provided with clutch teeth 85 which are arranged to be thrown into or out of mesh with a set of clutch teeth 86 formed integral with the gear 84.

It will be readily apparent from the foregoing disclosure that when the clutch member 77 is

10 moved toward the left, the shaft 73 will be connected directly to rotate the shaft 76 at the same speed. If a reduced or slower speed is required on the shaft 76, the clutch member 77 may be moved toward the right to throw the gear 78 into mesh with the gear 79 so that rotary motion of the shaft 73 will be transmitted through the gear 78, the gear 79, the shaft 80, and the gear 83, to rotate the gear 84 and the shaft 76 at a reduced or slower speed.

15 The right-hand end of the shaft 76 is rotatably supported by an anti-friction bearing 87 carried by the casing 70. The other end of the shaft 76 is rotatably journalled in a bearing bushing 88 formed in a hollow end portion of a rotatable shaft 89. The shaft 89 is journalled in an anti-friction bearing 90 supported by the casing 70. The shaft 89 serves as a support for a slidably mounted clutch member 91 having clutch teeth 92 which are arranged to be thrown into or out of engagement with a set of clutch teeth 93 formed on a clutch member 94 which is fixedly mounted on the right-hand end of the shaft 54 (Fig. 4). The clutch member 91 together with its associated parts serves as a stop and start clutch whereby the reciprocatory movement of the table 11 may be started and stopped as desired. A manually operable clutch shifting lever 95 on the front of the machine base is provided for actuating the clutch member 77 so that either a slow or a fast speed may be provided for traversing the table 11 at either a slow or a rapid speed as desired. A control lever 96 is mounted on the front of the machine base and serves as a stop and start lever for actuating the clutch 91 to stop and start the movement of the table 11 as desired.

20 The stop and start lever 96 is pivotally supported on a stud 97 which is in turn supported by a boss 98 which projects from the front of the base 10. The lower end of the lever 96 is connected by means of a stud 99 (Figs. 6 and 7) to the forward end of a slidably mounted plunger 100 which is journalled in a suitable bearing 101 formed in the base 10. The inner end of the plunger 100 is provided with a cam surface 102 which is arranged to engage a roller 103. The roller 103 is rotatably supported on a yoked member 104. The yoked member 104 is provided with diametrically opposed studs 105 and 106 which ride in a groove 107 formed in the clutch member 91. A tension spring 108 is connected between the yoked member 104 and a fixed portion of the machine base and serves normally to exert a thrust on the clutch member 91 tending to hold it in an engaged position. When it is desired to disengage the clutch member 91 to stop the table 11, the upper end of the lever 96 is rocked toward the base 10, that is, so that its downward end (Fig. 6) exerts an outward pull on the plunger 100 (Fig. 7) which moves the cam into engagement with the roller 103, after which continued movement serves through the roller to move the yoked member 104 toward the right (Fig. 7) to shift the clutch member 91 also toward the right to disengage the same, thus disconnecting the power drive to the table 11.

25 In order to attain one of the objects of the invention, a suitable shock absorbing device is provided to substantially eliminate the shocks and vibrations incident to reversing a rapidly reciprocating machine tool part. In the preferred construction, a fluid shock absorbing device is provided and is interposed between the

sleeve 60 and the drive shaft 61. The sleeve 60 is provided with an enlarged portion 110 within which are formed fluid chambers 111, 112, 113 and 114. A rotor 115 is contained within the chambers and is provided with diametrically opposed vanes 116 and 117. An inwardly projecting wall 118 is formed integral with the sleeve 60 and serves to separate the chamber 111 from the chamber 112. Similarly, an inwardly projecting partition 119 formed integral with the sleeve 60 serves to separate the fluid chambers 113 and 114. The chambers 111, 112, 113 and 114 are initially substantially filled with a fluid, such as a shock absorbing fluid or grease of the desired consistency and these chambers are maintained in a filled condition by injecting fluid or grease through the grease cups 120 and 121.

When the reversing clutch 53 (Fig. 4) is shifted in either direction to start the traversing movement of the table 11, the rotation of the sleeve 60 by means of the gearing above described first shifts the partitions 118 and 119 either in a clockwise or counterclockwise direction, the rotary motion of which cushions against the fluid or grease contained within the chambers 111, 112, 113 and 114 before rotation of the shaft 61 is started by the vanes 116 and 117. If the sleeve 60 is rotated in a clockwise direction (Fig. 5), the partition 118 will rotate and grease or fluid within the chamber 111 will squeeze out or be forced through between the inner face of the partition 118 and the peripheral face of the hub joining the vanes 116 and 117 into the chamber 112.

Similarly, fluid or grease within the chamber 113 will be placed under pressure and it will be squeezed or forced in part through the clearance space between the inner surface of the partition 119 and the peripheral surface of the hub 115. Due to this action of the grease or fluid within the chambers 111, 112, 113 and 114, each time the rotation of the worm shaft 40 is reversed by the automatic table actuated shifting of the reversing clutch 53, the fluid cushioning above described takes place before the worm starts rotating in the reverse direction, thus substantially eliminating the shocks and vibrations at reversal.

A dwell control mechanism is provided so that at reversal the table 11 may remain stationary at the end of its stroke in either direction to facilitate the grinding wheel grinding entirely around the work piece at its extreme end position before the table starts traversing in the reverse direction. This mechanism is preferably an electrically controlled mechanism actuated by and in timed relation with the table movement. A load and fire mechanism is provided for the clutch mechanism, comprising an arrow-pointed, spring-pressed plunger 125 carried by the downwardly extending arm 50. This arrow-pointed plunger rides on a roller 126 which is fixed relative to the base of the machine.

A rock arm 127 is rotatably supported on the sleeve 60 and is provided with a downwardly extending arm 128 having a projecting lug 129 which is adapted to fit within the groove 52 in the clutch member 53 when the clutch member is in a central or neutral position. The rock arm 127 is provided with an upwardly extending arm 130. A tension spring 131 is connected at its upper end to a lug 132 formed on the arm 130. The lower end of the spring 131 is connected to a stud 133 fixed to the casing 43. It will be readily apparent from the foregoing dis-

closure that the spring 131 normally tends to hold the lug 129 in engagement with the groove 52 in the clutch member 53.

A pull type solenoid 134 is connected by a stud 135 with the upper end of the arm 130 of the rock arm 127. A normally closed limit switch 136 is arranged to be opened at reversal by the upward movement of a plunger 137 which is actuated by means of a cam 138 carried by the hub of the lever arm 50. The solenoid 134 is normally maintained in an energized condition during the traversing movement of the table 11. Power lines 139 supply power to the solenoid 134. The solenoid 134 together with the normally closed limit switch 136 are interconnected with an electrical time delay relay 140 such as, for example, a Microflex time delay relay such as is manufactured by the Signal Electric Corporation. The solenoid 134, limit switch 136, and time relay 140 are so connected that when the reversing lever 45 is shifted by either of the table dogs 47 or 48 to cause a reversal in direction of movement of the table, the initial movement of the lever serves to disengage the clutch member 53 and at the same time, through the plunger 137, opens the normally closed limit switch 136 which breaks the circuit to deenergize the solenoid 134 and at the same time set the time relay 140 in motion. As soon as the solenoid 134 is deenergized, the released tension of the spring 131 serves to rock the rock arm 127 in a clockwise direction to move the downwardly extending lever 128 and the lug 129 into engagement with the groove 52 in the clutch member 53.

The mechanism is timed so that the lug 129 drops into the groove in the clutch member just as the arrow point 125 of the load and fire mechanism rides over the high point of the roller 126, so that the plunger 125 tends to shift the reversing clutch into the reverse direction, but such movement is prevented by engagement of the lug 129 with the groove 52 of the clutch 53. The parts remain in this position for a predetermined time interval as governed by the setting of the electric time delay relay 140. After the predetermined time interval has elapsed, the time relay 140 operates to close a circuit to energize the solenoid 134 which operates against the tension of the spring 131 to rock the rock arm 127 in a counterclockwise direction so as to withdraw the lug 129 from the groove 52 of the clutch 53. As soon as the lug 129 has been withdrawn, the released compression of the spring-pressed arrow point 127 immediately shifts the clutch 53 into its reverse position, thus starting the traversing movement of the table 11 in the opposite direction.

A grinding wheel feeding mechanism is provided to feed the wheel slide 25 together with the grinding wheel 27 supported thereby toward and from the table 11 to grind a cylindrical work piece supported thereby thereon. This feeding mechanism may comprise a half nut 145 depending from the under side of the wheel slide 25 which meshes with or engages a rotatable cross feed screw 146. The feed screw 146 is rotatably supported in bearings 147 (only one of which has been shown in the drawings) in the base 19. The outer end of the feed screw shaft supports a gear 148 (Fig. 3) which meshes with a small gear (not shown) which is supported to rotate with a manually operable feed wheel 149. The feed wheel 149 may be rotated to manually adjust the position of the wheel slide 25.

In order to feed the grinding wheel slide auto-

matically by power either at the ends of the work table reciprocatory stroke or continuously in case of a plunge-cut grinding operation, a feed pawl 150 is provided. The pawl 150 is oscillated by a mechanism to be hereinafter described while in engagement with a ratchet wheel or gear carried by the hand wheel 149. This part of the wheel feeding mechanism is an old and well known construction such as, for example, that shown in the expired patent to Norton, No. 762,838 dated June 14, 1904, to which reference may be had for details of disclosure not contained herein. The ratchet pawl 150 is connected by a connecting rod 151 with a crank plate 152 which is supported on a rotatable shaft 153. The shaft 153 is journaled in anti-friction bearings 154 and 155 in the base of the machine. The lower end of the connecting rod or link 151 is adjustably connected to the crank plate 152 and is arranged so that its connecting stud may be positioned in alignment with the axis of the shaft 153, in which case no motion is transmitted through the link 151 to oscillate the pawl 150, or may be adjusted eccentric relative to the axis of the shaft 153 to provide the desired oscillatory stroke to the feed pawl 150, as desired.

The shaft 153 is preferably operatively connected to be rotated by power either at a continuous rate of rotation for a plunge-cut infeed of the grinding wheel, or rotated intermittently at the ends of the work table stroke to provide an infeed in a traverse grinding operation. As shown in the drawings, a spiral gear 155 is rotatably supported on the shaft 153 (Fig. 3). The spiral gear 155 meshes with a spiral gear 156 (Figs. 3 and 4) which is formed integral with a shaft 157. The shaft 157 is journaled in bearings 158 and 159 which are in turn supported in the casing 70. A clutch member 160 is slidably keyed to the shaft 76. A gear 161 is formed integral with the clutch member 160 and is arranged to be thrown into or out of mesh with a gear 162 which is keyed to the shaft 157 (Fig. 4). A gear 163 is keyed to the shaft 157 and meshes with a gear 164 which is keyed to the shaft 89.

If it is desired to transmit a relatively slow rotation to the shaft 153, the clutch member 160 (Fig. 4) is shifted toward the right to mesh the gear 161 with the gear 162. In this position of the gears, a slow rotation will be imparted to the shaft 153 and also a slow rotation of the shaft 89 will be transmitted from the shaft 157 through the gears 163 and 164 to produce a slow traversing movement of the work supporting table 11. In case a rapid wheel feeding movement is desired in combination with a comparatively fast speed of the table 11, the clutch member 160 is moved toward the left (Fig. 4) so that clutch teeth on its left-hand end are thrown into mesh with clutch teeth 165 formed on the end of the shaft 89 and thus fixedly mounted relative to the gear 162. In this position of the parts, rotation of the shaft 76 will be transmitted directly to rotate the shaft 89 and through the connecting mechanism to traverse or reciprocate the table 11 at a comparatively fast speed. At the same time, the gear 164 will transmit a rotary motion through the gear 163 to rotate the spiral gear 156 which in turn rotates the spiral gear 155 at a comparatively fast rate of speed.

The slidably mounted clutch member 166 is keyed to the shaft 153 and is arranged so that it may be thrown into or out of engagement with clutch teeth 167 formed on the left-hand end face of the spiral gear member 155. When

the clutch member 166 is in a disengaged position, no rotary motion will be transmitted by the gear 155. A compression spring 168 surrounds a hub portion on the clutch member 166 and is interposed between a shoulder on the clutch member and a thrust collar 169 and serves to exert a pressure tending to hold the clutch member 166 in engagement with the clutch teeth 167.

The clutch member 166 is normally held in a disengaged position. The clutch member 166 is provided with a cam groove 170. A slidably mounted plunger 171 is normally maintained in the position shown in Fig. 3 in engagement with the cam groove 170 to hold the clutch 166 in its left-hand or disengaged position. When it is desired to obtain a feeding movement of the grinding wheel at the ends of the table stroke, it is necessary to withdraw the pin 171 so that the released compression of the spring 168 may throw the clutch 166 toward the right into engagement with the clutch teeth 167 so that the continuously rotating spiral gear 155 will impart an oscillating movement to the feed pawl 150, thereby producing an infeeding movement of the grinding wheel.

In order that the feeding movement of the grinding wheel may take place at the ends of the table stroke when the reversing mechanism is operative, it is desirable to provide an interlocking mechanism whereby the pin 171 may be instantaneously withdrawn from the cam groove 170 in timed relation with the movement of the reversing lever 45. The pin 171 is connected by a stud 172 which is carried by a rock arm 173. The rock arm 173 is pivotally supported on a stud 174 which is journaled in a bracket 175 within the machine base. A rock arm 176 is also supported by the stud 174 and is fixedly mounted to move with the rock arm 173 so that in effect the rock arms 173 and 176 constitute a bell crank lever. A detention spring 177 is connected between a stud 178 carried by the rock arm 176 and a stud 179 which is fixed relative to the base 10 of the machine. The tension of the spring 177 serves normally to exert a pressure on the bell crank lever 173—176 tending to hold the pin 171 within the cam groove 170.

A rock arm 180 (Fig. 6) is pivotally supported on a stud 181 which is fixed relative to the base 10. The right-hand end of the rock arm 180 is arranged in the path of an adjustable stop screw 182 carried by the rock arm 176. An adjustable rotatable stop cam 183 serves to limit the counterclockwise movement of the rock arm 180, thus limiting the clockwise movement of the bell crank lever 173—176. By adjustment of the screw 182, the position of the stud 171 may be varied relative to the cam path 170.

The rock arm 180 is provided with an adjustably positioned member 184 at its left-hand end which pivotally supports a pawl 185 which is arranged in the path of an arrow point 186 which is fixedly mounted on the rock shaft 46 so that it is moved by and in timed relation with the reversing lever 45. It will be readily apparent from the foregoing disclosure that each time the reversing lever is shifted at the ends of the table stroke, the arrow point 186 engaging the pawl 185 serves to rock the rock arm 180 in a clockwise direction. This movement in turn transmits a counterclockwise movement to the bell crank 173—176 to withdraw the pin 171 from the cam path 170, thus releasing the compression of the spring 168 to engage the clutch member 166 with the clutch teeth 167, and connecting the con-

tinuously rotated gear 155 with the shaft 153 to impart an infeeding movement to the grinding wheel slide 25 and the grinding wheel 27.

The withdrawal of the pin 171 is only for an instant. As soon as the arrow point 186 passes the center point, the released tension of the spring 177 tends to move the bell crank 173-176 in a clockwise direction. The pin 171 rides on the periphery of the clutch member 166 until it can drop into the cam slot 170. During this time interval the shaft 153 is only rotated a small portion of a complete rotation. The shaft continues to rotate until the cam slot 170 through the cam pin 171 again throws the clutch member 166 into a disengaged position (Fig. 3). It should be noted that when this mechanism is set for an infeeding movement at the end of the table stroke in a traverse grinding operation, the clutch 166 together with its actuating mechanism is arranged so that the shaft 153 will rotate only one completed rotation before the clutch 166 is again disengaged, thus providing an infeeding movement of the grinding wheel during the period of table reversal.

If it is desired to set up the machine for a 25 plunge-cut grinding operation, that is, for a continuous infeeding movement, a mechanism is provided for rendering the pin 171 inoperative so that the shaft 153 will be continuously rotated to impart a continuous oscillating movement to the feed pawl 150, thus continuously feeding the grinding wheel into the work piece. In order to accomplish this result, the cam or eccentric 183 is rotatably supported on a stud 187. An actuating knob 188 is mounted on the outer end of the stud 187. When it is desired to provide a plunge-cut grinding operation, the knob 188 may be rotated through 180 degrees, during which movement the eccentric 183 will rock the lever 180 in a clockwise direction and this in turn will rock the bell crank lever 173-176 in a counterclockwise direction so as to withdraw the pin 171, thus releasing the compression of the spring 168 which in turn throws the clutch member 166 into engagement with the clutch teeth 167. The parts will remain in this condition as long as desired. The continuous infeeding movement may be stopped and started either by rotation of the knob 188 or by actuation of the clutch member 166 (Fig. 4).

The operation of the improved cylindrical grinding machine will be readily apparent from the foregoing disclosure. Assuming all of the parts to have been previously adjusted, a work piece may be mounted in position on the headstock center 16 and footstock center 17, after which the grinding operation may be started. The table reciprocation may be started by actuation of the stop and start lever 96 which engages or disengages the clutch 91. At the ends of the table stroke as governed by the table dogs 47 and 48, a predetermined dwell may be obtained by adjustment of the time relay 140. Vibrations at reversal are substantially eliminated by means of the hydraulic shock absorbing device above described. The grinding wheel may be advanced at the ends of the reciprocatory stroke of the table 11 in a manner previously described. Each time the reversing lever 45 is shifted by the table dogs 47 and 48 to change the direction of movement of the table 11, the pin 171 is instantaneously withdrawn from the cam groove 170 so that the clutch is instantaneously connected to provide the desired infeeding movement of the wheel slide 25 and the grinding wheel 27. If it is desired to set 75

up the machine for a plunge-cut grinding operation, the work table remains stationary and a grinding wheel of a width equal to the length of the surface to be ground is mounted on the spindle 26. For such an operation, the knob 188 is rotated 180 degrees to render the pin 171 inoperative, thus providing a continuous rotation of the shaft 153 which serves continuously to oscillate the feed pawl 150, thus providing a continuous infeed of the grinding wheel.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a grinding machine having a base, a longitudinally reciprocable work supporting table, means including a reversing lever to reciprocate said table, a rotatable grinding wheel, a transversely movable wheel slide therefor, a wheel feeding mechanism including a continuously rotated power driven shaft to move said slide transversely, a clutch biased to an engaged position which is interposed between said shaft and wheel slide, means to hold said clutch disengaged during the longitudinal traversing movement of the table, and means actuated by said reversing lever during table reversal to release said clutch holding means to facilitate an infeeding movement of the grinding wheel.

2. In a grinding machine having a base, a longitudinally reciprocable table, means including a reversing lever to reciprocate said table, a rotatable grinding wheel, a transversely movable wheel slide therefor, a feeding mechanism therefor including a nut and screw mechanism, means including a continuously rotated power driven shaft to actuate said nut and screw mechanism, a clutch biased to an engaged position which is interposed between the nut and screw mechanism and the shaft, means to hold said clutch disengaged during the longitudinal movement of said table, and means actuated by said reversing lever during table reversal to release said clutch holding means to facilitate an infeeding movement of the grinding wheel.

3. In a grinding machine having a base, a longitudinally reciprocable work supporting table, means including a reversing lever to reciprocate said table, a rotatable grinding wheel, a transversely movable wheel slide therefor, a feeding mechanism therefor including a nut and screw mechanism, a pawl and ratchet mechanism to rotate said screw, a power driven mechanism to actuate said pawl, a spring engaged clutch between said power mechanism and said pawl and ratchet mechanism, means including a cam and a follower to hold said clutch disengaged during table reciprocation, and means actuated by said reversing lever instantaneously to withdraw the follower from engagement with said cam to provide an infeeding movement of the grinding wheel during reversal.

4. In a grinding machine having a base, a longitudinally reciprocable table, means including a reversing lever to reciprocate said table, a rotatable grinding wheel, a transversely movable

wheel slide therefor, a feeding mechanism therefor including a nut and screw mechanism, a pawl and ratchet mechanism to rotate said screw, a power driven mechanism to actuate said pawl, a normally engaged clutch therebetween, means including a cam and a follower to hold said clutch disengaged during the table reciprocation, yieldable means to maintain said follower in operative engagement with said cam, and means actuated by movement of the reverse lever instantaneously to withdraw said follower to provide an infeeding movement of the grinding wheel during reversal.

5. In a grinding machine having a base, a longitudinally reciprocable table, means including a reversing lever to reciprocate said table, a rotatable grinding wheel, a transversely movable wheel slide therefor, a feeding mechanism therefor including a nut and screw mechanism, a pawl and ratchet mechanism to rotate said screw, a power driven mechanism to actuate said pawl, a normally engaged clutch therebetween, means including a cam and a follower to hold said clutch disengaged during the table reciprocation, yieldable means to maintain said follower in operative engagement with said cam, and means actuated by movement of the reverse lever instantaneously to withdraw said follower to provide an infeeding movement of the grinding wheel during reversal, said cam being shaped automatically to disengage said clutch after one complete rotation thereof.

6. In a grinding machine having a transversely movable rotatable grinding wheel, a longitudinally reciprocable table, means including a table-actuated lever to reciprocate said table, a grinding wheel feeding mechanism including a rotatable feed screw and a nut, a power operated mechanism to rotate said screw, a clutch interposed between said power mechanism and screw, a spring automatically to engage said clutch, a cam on said clutch, a pivotally mounted follower engageable with said cam normally to hold said clutch disengaged, yieldable means normally to maintain said follower in engagement with said clutch, and means actuated by said reversing lever automatically to disengage said follower from said cam at each actuation of the reversing lever automatically to impart an infeeding movement of the grinding wheel during the table reversal.

7. In a grinding machine having a transversely movable rotatable grinding wheel, a longitudinally reciprocable table, means including a table-actuated reversing lever to reciprocate said table, a grinding wheel feeding mechanism including a rotatable feed screw and a nut, a power operated mechanism to rotate said screw, a clutch interposed between said power mechanism and screw, a compression spring automatically to engage said clutch, a cam on said clutch, a movable mounted follower engageable with said cam normally to hold said clutch disengaged, a spring normally to maintain said follower in engagement with said cam, and operative connections between said reversing lever and said follower whereby the follower is automatically disengaged from the cam at each actuation of the reversing lever automatically to impart an infeeding move-

ment to the grinding wheel when the table movement is reversed.

8. In a grinding machine having a base, a longitudinally reciprocable work supporting table, means including a reversing lever to reciprocate said table, a rotatable grinding wheel, a transversely movable wheel slide therefor, a feeding mechanism therefor including a nut and screw mechanism, a power driven mechanism to rotate said screw, a normally engaged clutch between said power mechanism and screw, means including a cam and a follower to hold said clutch disengaged during table movement, means actuated by said reversing lever instantaneously to withdraw said follower from engagement with said cam to provide an infeeding movement of the grinding wheel during reversal in a traverse grinding operation, and manually operable means to maintain said follower in an inoperative position to provide a continuous infeed of the grinding wheel for a plunge-cut grinding operation.

9. In a grinding machine having a transversely movable rotatable grinding wheel, a longitudinally reciprocable work supporting table, means including a reversing clutch to reciprocate said table, a groove in said clutch, a reversing lever operatively connected with said groove to actuate said clutch, a pivotally mounted latch which is yieldably biased to engage said clutch groove, a solenoid operatively connected to swing said latch out of engagement with said groove during the traversing movement of said table, a limit switch operatively connected with said solenoid, means actuated by said reversing lever to actuate said switch during reversal to actuate said solenoid so that the latch swings into engagement with said groove to hold the reversing clutch in a neutral position, and means including an electrical time delay relay which is set in motion by actuation of said switch to actuate the solenoid after a predetermined time interval, thereby withdrawing said latch from said groove so that the clutch may shift into a reverse position.

10. In a grinding machine having a transversely movable rotatable grinding wheel, a longitudinally reciprocable work supporting table, means including a reversing clutch to reciprocate said table, a groove in said clutch, a reversing lever operatively connected with said groove to actuate said clutch, a pivotally mounted latch which is yieldably biased in engagement with said clutch groove, a solenoid operatively connected to swing said latch out of engagement with said groove during the traversing movement of said table, a normally closed limit switch operatively connected with said solenoid, means actuated by said reversing lever to open said switch during reversal to deenergize said solenoid so that the latch swings into engagement with said groove to hold said clutch in a neutral position, and means including an electrical time delay relay which is set in motion by the opening of said switch to energize said solenoid after a predetermined time interval, thereby to withdraw said latch from said groove so that the clutch may shift into a reverse position.
